UNITED STATES PATENT OFFICE.

CATO HAARBERG, OF CHICAGO, ILLINOIS.

LIFTING DEVICE.

Application filed November 24, 1923, Serial No. 676,803. Renewed February 26, 1925.

To all whom it may concern:

Be it known that I, CATO HAARBERG, a citizen of the United States of America, and a resident of Chicago, in the county of Cook and State of Illinois, have invented a new and Improved Lifting Device, of which the following is a description.

My invention relates to a device for the lifting and carrying of either open or closed boxes or crates, as well as tubs, barrels, ice blocks, etc.

The general object of my invention is to provide a device comprising lift bars adapted to be grasped by two people at the front and back of the device being carried and having gripping means to engage the box, barrel, block, or other article being carried.

A more specific object of the invention is to provide a device of the indicated character readily adjustable to suit articles of different widths.

The nature of the invention and its distinguishing features and advantages will clearly appear as the description proceeds.

Reference is to be had to the accompanying drawings forming a part of this specification, it being understood that the drawings are merely illustrative of one example of the invention.

Figure 1 is a perspective view of a lifting device embodying my invention showing the same adjusted to and engaging a box;

Figure 2 is an end view on an enlarged scale;

Figure 3 is a fragmentary perspective view showing a portion of one of the lift bars and of the flexible means to connect the two bars.

In carrying out my invention in accordance with the illustrated example two lift bars 10 are provided having handles 11 at both ends of the bars.

A transverse flexible element 12 has connection with the bars at the center thereof, said element in the illustrated example being in the form of a chain. Said chain has suitable connection with the bars 10 and means is incorporated in the chain to adjust its total effective length to accord with the box A of a given width or other article to be carried. In the illustrated example a snap hook 13 is interposed in the chain and is adapted to engage in one of the links of the chain according to the width of the article to be carried.

Fixed to each block at the center is a grab

designated generally by the numeral 14, the shanks of said grabs in the illustrated example having right angular bends to accord with the cross section of the bars 10. In 60 the form shown a rivet 15 secures the shank to the bar and in addition at the bent end a screw 115 is employed. Thus, the grabs are disposed at the under side of the bars 10 and the bill or hook proper of each grab is directed downwardly and laterally inward to grip the side of the box, block, or the like, being carried.

As a practical means for securing the ends of the chain 12 the outer links thereof are 70 passed over the bills of the grabs and onto the shanks thereof to lie adjacent the outer side of the bars 10 and a retaining element 16 is provided on each bar at the outer surface and having its ends bent downwardly 75 toward the shank at the grab to retain the outer link of the chain against displacement while permitting its freedom of movement on the grab.

At its central portion each bar 10 is 80 formed with a member 17 projecting laterally outward as an extension so that with the bar positioned above the article to be carried the lateral projecting exerts a leverage on the grab and effectively engages it 85 with the article.

I would state in conclusion that while the illustrated example constitutes a practical embodiment of my invention, I do not limit myself strictly to the exact details herein 90 illustrated, since, manifestly, the same can be considerably varied without departure from the spirit of the invention as defined in the appended claims.

Having thus described my invention, I 95 claim:

1. A lifting device comprising a pair of elongated lift bars adapted to be disposed above an article to be carried and to be grasped at the ends thereof, a flexible transverse connection between said bars, and transversely disposed grabs on the bars at the approximate center thereof at the outer sides of the bars for engagement with the articles to be carried.

2. A lifting device comprising a pair of elongated lift bars, rigid transversely disposed grabs carried by said bars at the under sides thereof and extending laterally outward beyond the bars, said grabs presenting inwardly directed terminals, and a transverse connection between said bars.

3. A lifting device comprising a pair of elongated lift bars, grabs carried by said bars at the under sides thereof and extending laterally outward beyond the bars, said 5 grabs presenting inwardly directed terminals, a chain extending transversely between the bars, the said grabs being passed through the chain at the ends thereof, and elements on the bars to retain said chain against displacement.

4. A lifting device comprising a pair of connected lifting bars having grabs rigid therewith adapted to engage an article to be carried, said grabs being disposed transversely to the bars and extending laterally 10 beyond the outer sides of the respective bars.

5. A lifting device comprising a pair of connected lifting bars having rigid grabs adapted to engage an article to be carried, said grabs disposed at the under side of the 20 bars and projecting laterally outward beyond the same, the terminals of said grabs being directed laterally inward.

6. A lifting device comprising a pair of elongated connected bars having members at 25 the approximate center thereof projecting laterally outward, and rigid grabs on the bars at the under side and extending laterally outward beyond said members to be subject to the leverage exerted by said members when the bars are lifted.

CATO HAARBERG.
